UNITED STATES PATENT OFFICE.

CHARLES R. HAY, OF SAN FRANCISCO, CALIFORNIA, ASSIGNOR OF ONE-HALF
TO R. H. MARCHANT, OF SAME PLACE.

CAN-PRINTING DEVICE.

SPECIFICATION forming part of Letters Patent No. 431,165, dated July 1, 1890.

Application filed November 22, 1889. Serial No. 331,231. (No model.)

To all whom it may concern:

Be it known that I, CHARLES R. HAY, a citizen of the United States, residing in the city and county of San Francisco, State of California, have invented an Improvement in Can-Printing Devices; and I hereby declare the following to be a full, clear, and exact description of the same.

My invention relates to a novel device for printing upon the exterior surface of cans, and it is especially applicable to take the place of labels for cans containing fruit, fish, or other substances which are usually packed in hermetically-sealed cans and afterward labeled by pasting paper labels upon them.

My invention consists in certain details of construction, which will be more fully explained by reference to the accompanying drawings, in which—

Figure 1 is a general view of my apparatus. Fig. 2 is a transverse section. Fig. 3 is a detailed view of the can-holder.

A is a suitable frame-work for supporting the various parts of the mechanism, and B are grooved guides or channels formed in the upper horizontal side timbers of the frame. Within these guides the arms C are fitted to travel, these arms forming the frame from which the carrier D is suspended. This carrier is supported from the arms C by elastic springs E, which allow it to rise and fall and accommodate itself to the surface of the can as it passes over it.

F is the printing block or type, which is constructed of any flexible substance and suitably fixed upon the bed of the machine.

G is an inking-plate, and H an inking-roller. This inking-roller is suspended by arms I, which are suitably connected with the rearmost of the sliding bars or guides C. The roller proper is journaled upon a yoke J, which has a stem K, extending upward from its central portion and surrounded by a spiral spring L. The rod or stem K slides through the upper end of the suspending frame-work, and the action of the spring L is to press upon the yoke J and hold the roller H down with an elastic pressure.

Whenever the carrier D is moved forward, by grasping the handle C', which unites the

slides C, the inking-roller H will be dragged first across the inking-plate G and then across the printing-surface F, so as to prepare it at each time for printing.

The cans M are placed in a carrier N, which consists of a segment of sufficient length to receive the can and mounted by means of lugs O upon a pin P, about which it is allowed to swivel or turn. A stud Q extends down from the front of the carrier N and is surrounded by a spiral spring R, the lower end of which rests upon the sliding support S of the can-holder. It will be seen that by this construction the can-holder may be tilted forward by pressure upon its front portion, and the spring R will be compressed to allow it to tilt; but after it is released the spring will return it to its former position. This can-holder is mounted, as before described, upon the transversely-moving slide S, which travels in suitable guides T just in front of the flexible printing plate or surface F. One of the ends of the can-holder N is made just high enough to form a stop when the can is put into the holder. The other head U is made movable, and is adjusted by means of a screw V, passing through the stationary head W, so that by turning the screw the movable head U may be adjusted to suit any length of can which is to be placed in the holder.

Beneath the slide S is a spring X, extending transversely and parallel with the line of travel of the slide S.

The operation of the machine will then be as follows: By the action of the spring X the can-holder N and its slide are drawn to one side of the machine, so that a can may be placed in the holder. The holder is then pushed in until the can is within the frame of the machine and in line with the printing-block F. With the other hand the operator then grasps the handle C' and moves the carrier D forward. The front edge of the carrier striking the can causes the holder N to tilt about its fulcrum-shaft P, and thus allow the can to roll out, and the continued action of the carrier D rolls the can across the printing-surface F, so that the surface of the can will be printed upon, after which it rolls off at the end of the flexible printing-

block and may be suitably disposed of. As soon as the can has left the holder the latter is released, and the action of the spring X immediately draws it out to one side of the frame, and this allows the inking-roller H, which has passed over the inking-plate G, to follow on and pass over the printing-surface F, thus preparing it for the next can.

If it is desired to print in more than one color, I employ a marker or guide Y, which projects upwardly from the slide U of the can-holder and has a point or indicator to which the can may be adjusted for the first printing, and afterward adjusted to the same point for printing the second color, so that the colors will register exactly. By means of this device I am enabled to print labels upon cans containing hermetically-sealed goods with great rapidity, and the expense and time needed for putting on proper labels is avoided.

Having thus described my invention, what I claim as new, and desire to secure by Letters Patent, is—

1. A printing block or surface, an inking-plate, and an inking-roller arranged as shown, a holder into which the can may be introduced and from which it may be delivered so as to roll over the printing-surface, and a moving carrier traveling in guides above the can, whereby the can may be moved out of its holder and caused to roll across the printing-surface, substantially as herein described.

2. A printing-surface, an inking-plate arranged upon a bed, one behind the other, a tilting can-holder adapted to slide transversely across said bed, so as to receive a can and to hold it in line with the printing-surface, a carrier traveling in guides above the printing-bed and having an inking-roller suspended from it so as to travel over the inking-plate and the printing-surface, and a handle, whereby the carrier may be moved along the slides, substantially and for the purpose herein described.

3. A printing-surface fixed upon the bed, a can-holder mounted upon a transversely-moving slide, whereby it may be withdrawn to one side of the printing-bed to receive the can and move forward into line with the printing-surface, a hinged support for said

carrier, and a spring connecting to hold it upright and return it to that position after it has been tilted to discharge the can, substantially as herein described.

4. A can-holder mounted upon a transversely-moving slide so as to tilt forward and discharge the can, a spring whereby it is returned to its upright position after the can is discharged, and a transverse spring acting upon the slide upon which the can-holder is mounted so as to withdraw the slide and holder to one side of the machine whenever it is released, substantially as herein described.

5. The can-carrier, consisting of a plate suspended by elastic springs from a carrying-yoke, slides traveling in horizontal guides above the printing-table and having said yokes attached to them, so that the forward movement of the carrier will cause it to engage the surface of the can and roll the latter over the printing-surface, substantially as herein described.

6. The improvement in labeling cylindrical cans, consisting of a fixed printing-surface, a tilting holder into which the can is placed, and a horizontally-moving carrier adapted to move above the can, whereby the can is caused to roll across the printing-surface and be imprinted thereby, substantially as herein described.

7. A fixed printing-surface, a transversely-moving can-holder adapted to tilt so as to deliver the can upon the printing-surface, a horizontally-moving carrier guided so as to travel above and in contact with the top of the can, an inking-plate situated behind the printing-surface, and the flexibly-suspended inking-roller suspended from the carrier-frame so as to travel over the inking-plate and the printing-surface when the carrier-frame is moved forward and after the can-carrier has been withdrawn from its line of travel, substantially as herein described.

In witness whereof I have hereunto set my hand.

CHAS. R. HAY.
